US0D1109768S

(12) **United States Design Patent** (10) Patent No.: **US D1,109,768 S**
 Arseneault et al.

(54) **DISPLAY SCREEN OR PORTION THEREOF
WITH GRAPHICAL USER INTERFACE**

(71) Applicant: **ILLUMINA, INC.**, San Diego, CA (US)

(72) Inventors: **Max Arseneault**, San Diego, CA (US);
Andrew Walker, Houston, TX (US);
Andrew Warren, Carlsbad, CA (US)

(73) Assignee: **Illumina, Inc.**, San Diego, CA (US)

(**) Term: **15 Years**

(21) Appl. No.: **29/879,431**

(22) Filed: **Jul. 7, 2023**

(51) LOC (15) Cl. **14-04**

(52) U.S. Cl.

(57) **CLAIM**

The ornamental design for a display screen or portion thereof with graphical user interface, as shown and described.

DESCRIPTION

The FIGURE depicts a display screen or portion thereof with graphical user interface, showing our new design. The outermost broken lines show a display screen or portion thereof and form no part of the claimed design. The broken lines within the FIGURE show portions of the graphical user interface or portion thereof which form no part of the claim.

1 Claim, 1 Drawing Sheet
